ENDOSCOPIC INSTRUMENT

Frederick Charles Wappler, New York, N. Y.

Application November 6, 1931, Serial No. 573,389

9 Claims. (Cl. 174—89)

My present invention relates generally to surgical instruments, and has particular reference to an improved endoscopic instrument.

It is a general object of my invention to provide 5 an improved endoscope of the type which is adapted to accommodate a longitudinally movable electrode rod having an operative loop arranged transversely and adapted to project laterally out of a fenestra in the endoscopic tube. 10 It is a more particular object to provide an improved device wherein a transversely arranged electrode loop may be caused more efficiently to fulfill a contemplated cutting or resecting function in connection with internal operations of this 15 character. Thus, where an instrument of the present type is used to resect a longitudinal channel or the like through an internal protrusion, the endoscope is arranged to engage such protrusion; and when the electrode rod is moved longitudinally, the operative loop resects the desired channel in a more expeditious and reliable manner.

A particular feature of my invention lies in the provision of means whereby the operative loop is 20 caused to complete its cutting or resecting operation in shearing relationship with an end edge of the endoscopic fenestra through which it projects. The shearing action thus provided for is 25 of great advantage in efficiently and reliably finishing off the cutting operation which is being performed.

A further and more particular feature of my invention lies in providing a yieldable means 30 which constantly urges the operative loop laterally out of the fenestra, in combination with a means for guiding or camming the operative loop inwardly during the completion of its cutting operation, whereby the loop is brought into 35 shearing relationship with an edge of the fenestra.

Another feature of my invention lies in providing 40 an endoscopic tube designed primarily for use in conjunction with an electrode rod of the present character, the tube having a lateral fenestra whereof at least one end edge is of insulating material. In a preferred embodiment, the rear edge of the fenestra is insulated so that the 45 shearing operation takes place at the conclusion of a rearward sweep or movement of the electrode rod. Preferably, the entire endoscopic tube is of insulating material so that the shearing engagement of the uninsulated operative loop with the edge of the fenestra may be effected without any 50 interference with the desired or necessary electrical connections.

I achieve the foregoing objects, and such other objects as may hereinafter appear or be pointed out, in the manner illustratively exemplified in the accompanying drawing, wherein—

Figure 1 is a perspective view of one type of 5 endoscopic instrument embodying the features of my present invention;

Figure 2 is an enlarged elevational cross-section of the forward end of the instrument;

Figure 3 is a fragmentary view taken from the 10 bottom of Figure 2;

Figure 4 is a fragmentary end view; and

Figures 5-8 are cross-sectional views taken substantially along the corresponding lines indicated in Figure 2 and illustrating the manner in which 15 the electrode loop is guided.

The endoscopic tube 10 is provided at its forward end with a lateral fenestra 11 and is shown, in Figure 1, combined with the more or less conventional type of associated parts. Petcocks 12 20 control the irrigation. A telescopic tube 13 is supported in a mounting 14 secured to the tube 10 by any suitable means, such as the clamp 15. At its rear end, the telescope is provided with an eyepiece 16. Beneath the telescope means 25 are provided for accommodating and receiving an electrode rod 17 adapted to be moved longitudinally in the endoscope 10 by means, for example, of the handle 18.

The telescope is preferably of the character 30 illustrated and described in United States Letters Patent No. 1,680,491, having an electric lamp 19 at its forward tip and provided with an operative lens 20 which commands an obliquely forward field of vision.

The electrode rod 21 is preferably insulated and is guided in its movements by means of a substantially hemispherical fin 22 which preferably engages the telescope 13 by means of one or more clips 23 or the like.

The forward portion 24 of the fin 22 hangs free, and is constructed of resilient material shaped to assume substantially the position of Figure 2 under normal conditions. It is to be noted that this free end 24 serves as a spring 45 which bears yieldably against the electrode rod 21 near the forward end of the instrument so as to urge the rod 21 laterally against the fenestrated wall of the tube 10.

At its forward end, the rod 21 is provided 50 with an operative, uninsulated loop 25 which is substantially U-shaped and arranged in a plane substantially transverse to the axis of the tube 10. The loop 25 is preferably supported at the ends of two forwardly divergent arms 26 shown 55

most clearly in Figure 3, these arms being ensheathed in relatively thin insulating material and extending rearwardly into the body of the electrode rod 21.

5 The parts are so constructed that when the rod 21 is advanced, as shown in full-lines in Figures 2-4, the loop 25 will project laterally out of the fenestra 11. It is to be noted that this lateral projection is one which brings the 10 loop out of the fenestra across the imaginary continuation of the shorter endoscope wall. This is shown most clearly in Figure 4. In the absence of my present construction, the rearward movement of an electrode rod under these conditions would bring the operative portion thereof 15 into abutting relationship with the wall of the endoscope. Further rearward movement would be thereby impeded, and no shearing action of any character would be accomplished by the loop.

20 In accordance with my present invention, the loop is so shaped as to be capable of effecting a shearing action in connection with the rear edge 27 of the fenestra 11; and the spring 24, in conjunction with the specially constructed arms 26, 25 and in conjunction with the specially configured walls of the fenestra 11, afford a means for automatically camming the operative loop inwardly during the retraction of the rod 21, whereby the 30 loop is gradually brought into the positions shown in dot-and-dash lines in Figure 2 during the rearward movement thereof. It is to be noted that in the extreme right dot-and-dash position of Figure 2, indicated also in Figure 8, the loop 25 has been brought into direct shearing relationship with respect to the edge 27. This efficiently and reliably completes and finishes off any 35 cut which the operative loop has been engaged in resecting.

40 The manner in which this desirable effect is achieved is indicated most clearly in Figures 2-8. When the rod 21 is advanced, the loop 25 is permitted to assume the laterally projecting position of Figures 2, 3 and 4. It is positively urged into this position by the action of the 45 spring 24. After the rod 21 is retracted, the arms 26 engage slidably with the side walls of the fenestra 11, whereby a camming action takes place since the arms 26 converge rearwardly. This 50 camming action is indicated in Figures 5-8, and results from the fact that the arms 26 automatically seek to accommodate themselves in the wider portion of the tube 10. When the rod 21 is advanced, as shown in full-lines in Figure 2, there is no constriction upon the arms 26 and the 55 spring 24 pushes the loop 25 laterally to its fullest extent. As the rod 21 is retracted, however, the arms 26 must either yield or move radially into the tube 10 against the action of the spring 24 because of the camming engagement of these 60 arms with the walls of the fenestra 11.

65 As a result the loop 25 does not terminate its rearward movement in abutting encounter with the edge 27 but, on the contrary, is guided or cammed inwardly in a gradual manner so that the rearward movement terminates in a shearing action between the loop 25 and the edge 27.

70 Although I have illustrated this desirable effect as being accomplished during a retraction of the rod 21, nevertheless it will be understood that, under certain circumstances, the parts may be so arranged that this action will take place under a forward movement of the rod 21. In such an event, the lateral fenestra 11 would not flare forwardly into the oblique relationship illustrated,

but would terminate in a forward edge corresponding to the rear edge 27.

Furthermore, it will be understood that, although I have shown the entire tube 10 composed of insulating material, nevertheless only the edge portion, and especially the end edge portion, of the fenestra need be of insulating material.

10 It will also be understood that, although I have designated the arms 26 as being unyieldable, and although the action of the device is dependent in a large measure upon this unyieldability, nevertheless a certain flexibility and resilience is inherently present and not only fails to interfere with the contemplated movements but definitely facilitates the desired operation.

15 The spring 24 may, of course, be provided in any desired manner, and the illustrated construction is shown merely by way of example and is preferred.

20 In general, it will be understood that changes in the details herein described and illustrated for the purpose of explaining the nature of my invention may be made by those skilled in the art without departing from the spirit and scope of the invention as expressed in the appended claims. 25 It is therefore intended that these details be interpreted as illustrative, and not in a limiting sense.

20 Having thus described my invention and illustrated its use, what I claim as new and desire to 30 secure by Letters Patent is—

35 1. An instrument of the character described, comprising an endoscopic tube having a lateral fenestra, a longitudinally movable electrode rod in said tube and provided with an operative, high-frequency, resecting loop arranged in a plane substantially transverse to the axis of the tube, yieldable means in said tube for urging said loop laterally out of said fenestra, and means for camming said loop inwardly against the action of said 40 yieldable means when the electrode rod completes its operative, longitudinal movement, so as to bring the loop into shearing relationship with an end edge of said fenestra.

45 2. An instrument of the character described, comprising an endoscopic tube having a lateral fenestra, a longitudinally movable electrode rod in said tube and provided with an operative, high-frequency, resecting loop arranged in a plane substantially transverse to the axis of the tube, yieldable means in said tube for urging said loop laterally out of said fenestra when the electrode rod is advanced, and means for camming said loop 50 inwardly against the action of said yieldable means when the electrode rod completes its operative, retractive movement, so as to bring the loop into shearing relationship with the rear edge 55 of said fenestra.

60 3. An instrument of the character described, comprising an endoscopic tube having a lateral fenestra, a longitudinally movable electrode rod in said tube and provided with an operative, high-frequency, resecting loop arranged in a plane substantially transverse to the axis of the tube, yieldable means in said tube for urging said loop laterally out of said fenestra, and means associated 65 with the loop and engaging the walls of the fenestra for camming the loop inwardly against the action of said yieldable means when the electrode rod completes its operative, longitudinal movement, whereby the loop is brought into shearing relationship with an end edge of said fenestra.

70 4. An instrument of the character described, comprising an endoscopic tube having a lateral fenestra, a longitudinally movable electrode rod 75
